UNITED STATES PATENT OFFICE.

JOHN CUNNINGHAM, OF CHICAGO, ILLINOIS, ASSIGNOR TO ANDERSON FOWLER, OF SAME PLACE.

APPARATUS FOR SINGEING HOGS.

SPECIFICATION forming part of Letters Patent No. 430,769, dated June 24, 1890.

Application filed December 7, 1889. Serial No. 332,932. (No model.)

To all whom it may concern:

Be it known that I, JOHN CUNNINGHAM, residing at Chicago, in the county of Cook and State of Illinois, and a citizen of the United States, have invented a new and useful Improvement in Apparatus for Singeing Hogs, of which the following is a specification, reference being had to the accompanying drawings, in which—

10 Figure 1 is a vertical section through the center of the furnace and singeing-chamber. Fig. 2 is a section at line 2 of Fig. 1. Fig. 3 is a side elevation showing the furnace, the arrangement of the endless chains, and a tank 15 for cooling the chains, which tank is in section.

It is common to singe the carcasses of hogs when preparing them for the market. This has heretofore been accomplished by means 20 of a cylindrical chamber heated by means of furnaces arranged outside of such chamber, coal being used in the furnaces, and the hogs have been lifted up into the chamber through an opening at the bottom thereof and then 25 taken out through the same opening. This manner of heating the chamber is expensive and the singeing operation is comparatively slow.

The objects of my improvement are to provide 30 an improved furnace and singeing-chamber adapted to be heated by the use of petroleum, and improved devices for carrying the hogs into and away from the singeing-chamber, which I accomplish as illustrated in the drawings and as hereinafter described.

That which I claim as new will be set forth in the claims.

In the drawings, A is the wall of a furnace 40 and singeing-chamber R, supposed, for convenience, to be located on the second floor of a building.

It may be supposed to represent the floor upon which the singeing-chamber is placed, 45 although in the drawings suitable supports for this floor are not shown.

The wall of the furnace may be of brick about sixteen inches thick. In this wall and near the bottom there is an annular chamber 50 b, from which there are a number of openings

or passages c, leading to the interior of the singeing-chamber.

B is a pipe through which and through the burners or tubes r petroleum can flow into the chamber b.

55

d' are two vertical recesses in opposite sides of the wall of the furnace, in which recesses the endless chains used to convey the hogs through the singeing-chamber pass for the purpose of protecting the chains somewhat 60 from the intense heat in the chamber.

C D are two doors hinged to the wall A, which doors open outward, and they are so hung that they close by gravity. There is an opening e in the bottom of the furnace. 65

f g are two doors which are hung at the bottom of the furnace, so as to open downward, which doors can be closed by hand or otherwise when desired.

E is the outlet for the products of combustion. 70

F G are two endless chains which run over sprocket-wheels suitably located, one of which H is shown, which sprocket-wheels are driven in any known suitable manner, the driving devices not being shown. 75

h i are two pulleys located in small chambers or recesses provided therefor at or near the top of the singeing-chamber, which pulleys may be supported on studs secured in the wall of such chamber. 80

j k l m are other guide-pulleys for one of the chains, similar guide-pulleys being provided for the other chain.

I are metal bars connected with the chains at suitable intervals. 85

J is a tank for water, through which the chains pass in order to cool them.

K is an inclined platform.

n is an opening for the purpose of giving 90 access to the chamber b for the purpose of lighting the petroleum flowing from one of the tubes r. When the petroleum from this tube has been ignited, the flame will pass around in the chamber b and the petroleum 95 from the other tubes r will be ignited.

The operation is as follows: Petroleum is to be admitted into the chamber b through the tubes r, and being ignited the flames will pass through the openings c into the singeing-chamber. 100

ing-chamber R. The hogs to be singed can most conveniently be brought to a point near to the chains F G and in the room below the place where the furnace is located by being 5 conveyed on a track or rail, as is usual. The hogs one after another are to be hooked onto one of the bars I, and the chains being in motion the hogs will be carried up one after another into and through the singeing-chamber R, and in passing through such chamber will be thoroughly singed. The movement 10 of the chains will bring the hogs one after another into contact with the doors C D on the inside, causing them to open, and the 15 hogs will pass out through the doors and be carried to the inclined platform K, at which point an attendant releases them from the bars I. The chains pass through water in the tank J and are cooled.

20 By constructing a furnace and singeing-chamber substantially as described, and using petroleum for fuel, there will be a great saving in the expense of the fuel, and as the chains which carry the hogs move continuously 25 in one direction the operation of singeing will be very much more rapid than by the old method.

I do not limit myself to a furnace constructed exactly as shown and described.

30 The essential feature of my invention, so far as the furnace proper is concerned, consists in providing a chamber in which petroleum can be ignited and from which the flames will pass into the singeing-chamber, there to 35 come in contact with the hogs as they are carried by the chains through the chamber.

I have shown four jets for petroleum. A greater or less number may be used. The flow of petroleum to the chamber b is to be 40 regulated in any usual manner.

What I claim as new, and desire to secure by Letters Patent, is as follows:

1. A singeing-furnace consisting of a furnace-wall inclosing a singeing-chamber and 45 having a bottom inlet and an exit above for the carcasses and constructed with a liquid-fuel-ignition chamber and lateral flame-orifices opening into the singeing-chamber, a liquid-fuel-supply pipe for the ignition-chamber, and vertically-traveling chains having 50

carcass-supports for carrying the carcasses into the bottom inlet, upwardly through the singeing-chamber, and out at the exit, substantially as described.

2. A singeing-furnace consisting of a furnace-wall A, inclosing a singeing-chamber R, provided with an outwardly-swinging door near the top and having an annular liquid-fuel-ignition chamber b and lateral flame-orifices c, communicating with the annular 60 chamber and opening into the singeing-chamber, a liquid-fuel-supply pipe for the annular chamber, and mechanism for carrying the carcasses vertically through the singeing-chamber and laterally through the furnace-wall at the outwardly-swinging door, substantially as described. 65

3. A singeing-furnace consisting of a furnace-wall A, inclosing a singeing-chamber R and having an outwardly-swinging door, an annular liquid-fuel chamber b, and a series of flame-orifices c, communicating with the annular chamber and opening into the singeing-chamber, a liquid-fuel-supply pipe B, and traveling endless chains F and G, which carry 70 the carcasses vertically through the singeing-chamber and laterally therefrom through the furnace-wall, substantially as described. 75

4. A singeing-furnace consisting of a furnace-wall A, inclosing a singeing-chamber R 80 and formed with the annular fuel-ignition chamber b and vertical oppositely-arranged chain recesses or channels d d', a liquid-fuel-supply pipe B, and the endless carcass-carrying chains F and G, traveling vertically 85 through the recesses or channels and having devices for engaging and moving the carcass upwardly through the singeing-chamber, substantially as described.

5. A furnace and singeing-chamber having 90 recesses d d' in the wall thereof, in combination with endless chains F G, running in such recesses and over suitable guide-rollers and provided with bars for supporting the carcasses, substantially as and for the purpose 95 specified.

JOHN CUNNINGHAM.
